UNITED STATES PATENT OFFICE.

ROSS GEORGE SMITH, OF DERRY VILLAGE, NEW HAMPSHIRE, ASSIGNOR TO RAYMOND, PYNCHON & COMPANY, OF NEW YORK, N. Y.

MANUFACTURE OF EXPLOSIVES.

1,243,231.

Specification of Letters Patent.

Patented Oct. 16, 1917.

No Drawing.

Application filed February 3, 1916. Serial No. 75,909.

To all whom it may concern:

Be it known that I, ROSS GEORGE SMITH, a citizen of the United States of America, residing at Derry Village, county of Rockingham, State of New Hampshire, have invented certain new and useful Improvements in the Manufacture of Explosives, of which the following is a specification.

This invention relates to high explosives of the perchlorate type, suitable for use in mines, shells or bombs, and for blasting or other purposes.

According to this invention a mixture of ammonium perchlorate and finely divided zinc such as zinc dust is employed, together with suitable carbon compounds which are not liable to reduction by the zinc. No nitrates or nitro compounds are used, as these are attacked by the zinc and render the latter useless. Chlorates are also avoided. It is essential that the zinc powder remain unaffected until the explosive is detonated and the perchlorate is a stable compound which does not react with the zinc under normal conditions. It has been discovered on the other hand, that not only do nitrates and nitro compounds react with the zinc, but that chlorates, which have been proposed for use in an explosive employing zinc, act in a manner quite different from perchlorates which are therefore not equivalents in an explosive of this type. Ammonium chlorate is moreover in itself an unstable compound and cannot be employed owing to the fact that it undergoes spontaneous decomposition. The present invention is based on the discovery that ammonium perchlorate can be employed as the oxidizing agent in a zinc powder explosive only if the more usual oxidizing agents, the chlorates and nitrates, are absent.

The carbon compounds preferred are petroleum jelly or other solid or liquid hydrocarbon and asphaltum varnish or tarry material, such as tar oil with or without the addition of benzol or alcohol. The asphaltum varnish contains some sulfur and this is desirable, so that where tarry material free from sulfur is used a small quantity of sulfur, up to say 5% of the said material, may be added. The varnish or equivalent substance acts as a water-proofing

and air-proofing material to prevent oxidation of the zinc or its contact with any small quantities of substances in the explosive mixture which may be reduced by the zinc.

The following composition contains typical proportions of the ingredients for 100 lbs. of a powerful explosive prepared according to this invention: ammonium perchlorate, 82 lbs.; zinc dust, 10 lbs.; petroleum jelly, 5 lbs.; asphaltum varnish, 3 lbs. The powdered ingredients are mixed together and the petroleum jelly and asphaltum varnish added in succession and intimately mixed in. Some alterations in the proportions of the ingredients and in the nature of the organic materials may be made to produce any special characteristics which may be desired. It is found that an explosive prepared in this manner possesses not only great stability but detonates perfectly, so that no particles are left unexploded even in the open air.

What I claim and desire to secure by Letters Patent of the United States is:—

1. An explosive composition consisting of finely divided zinc, a combustible carbon compound which is stable in the presence of zinc, and ammonium perchlorate in sufficient quantity to oxidize the other ingredients, no chlorates, nitrates or nitro compounds being present.

2. An explosive composition consisting of finely divided zinc, petroleum jelly, a waterproofing organic compound, and ammonium perchlorate in sufficient quantity to oxidize the other ingredients, no chlorates, nitrates or nitro compounds being present.

3. An explosive composition consisting of finely divided zinc, petroleum jelly, asphaltum varnish, and ammonium perchlorate in sufficient quantity to oxidize the other ingredients, no chlorates, nitrates or nitro compounds being present.

4. An explosive composition consisting of the following ingredients in approximately the following proportions:—ammonium perchlorate, 82 lbs.; finely divided zinc 10 lbs.; petroleum jelly, 5 lbs.; asphaltum varnish, 3 lbs.

In testimony whereof I herewith affix my signature.

ROSS GEORGE SMITH.
